(57) CLAIM

The ornamental design for a watch, as shown and described.

DESCRIPTION

FIG. 1 is a right front perspective view of a watch showing my new design;

FIG. 2 is a left front perspective view thereof;

FIG. 3 is a front elevational view thereof;

FIG. 4 is a right front perspective view thereof in a second environment;

FIG. 5 is a left front elevational view thereof in a second environment; and,

FIG. 6 is a front elevational view thereof in a second environment.

The broken line showings of watchbands in FIGS. 1-6 are environmental only and form no part of the claimed design.

1 Claim, 6 Drawing Sheets

FIG. 1

FIG. 2

FIG. 3

FIG. 4

FIG. 5

FIG. 6
